CLAIM

I claim the ornamental design for a calibration support for a vehicle, as shown and described.

DESCRIPTION

FIG. 1 is a front elevational view of a calibration support for a vehicle showing my new design;

FIG. 2 is a back elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view thereof;

FIG. 8 is another perspective view thereof;

FIG. 9 is a front elevational view thereof in a changed status;

FIG. 10 is a back elevational view thereof in a changed status;

FIG. 11 is a left side elevational view thereof in a changed status;

FIG. 12 is a right side elevational view thereof in a changed status;

FIG. 13 is a top plan view thereof in a changed status;

FIG. 14 is a bottom plan view thereof in a changed status;

FIG. 15 is a perspective view thereof in a changed status; and,

FIG. 16 is another perspective view thereof in a changed status. The broken lines in the drawings illustrate portions of the calibration support for a vehicle that form no part of the claimed design.
